UNITED STATES PATENT OFFICE

FRANK BINSFELD, OF ST. GREGOR, SASKATCHEWAN, CANADA

BURNER

Application filed August 14, 1928. Serial No. 299,609.

This invention relates to improvements in a burner for use with various commercial gasoline lamps at present on the market. Its primary object is to provide a burner that 5 will not readily become inoperative by the collection of carbon on the said burner. Provision being made on the lower side of the burner for the carbon to settle, where it will not affect the operation of the lamp.

10 A further object is to provide a screen within the said burner that will atomize and assist in vaporizing the gasoline as it is forced from the gasoline chamber to the burner.

A still further object is to provide a burner 15 of the type set forth that is easily disassembled for cleaning or any other purpose.

With these and other objects in view as will appear as the description proceeds the invention consists in the novel construction and 20 arrangement of parts as hereinafter more specifically set forth, claimed and shown in the accompanying drawings forming a part of this present application and in which:

Fig. 1 is a perspective view of my invention. 25 Fig. 2 is an enlarged partial cross section view through the same.

Fig. 3 is an enlarged perspective view of the burner tip.

Fig. 4 is an underneath plan view of the 30 burner tip showing the rounded part.

Referring more in detail to the drawings in which similar reference characters designate corresponding parts throughout the several views, it will be seen that the invention 35 consists of a tube 10 with a nut 11, and thread 12 whereby the burner is connected to the gasoline lamp. A screen 13 is placed inside the tube 10 and is held in place by a projection 14 in the tube 10. The said screen 40 is made up of a number of layers of very fine mesh screen wire secured together and provided with a small loop 15 by which the screen may be withdrawn from the tube for cleansing.

45 The upper end of the tube 10 is provided with an internal thread 16, into which the burner tip 17 is screwed. This burner tip 17 is provided with a hole 18 through its center which is slightly conical in shape. The inner end of the burner tip 17 is rounded

as shown at 19, the small end of the hole 18 being located at the lowest point of this part 19, around which the carbon will settle when the lamp is in operation.

It is believed that the construction and advantages of the structure shown may be apparent from the foregoing paragraphs, taken in conjunction with the accompanying drawings without further detailed description.

While the preferred embodiment of the invention has been disclosed it is understood that minor changes in the details of construction, combination and arrangement of co-operating elements may be resorted to within the scope of what is claimed without departing from the spirit of the invention.

What I claim is:—

In a gasoline lamp burner of the type described having a tubular member with a nut and external thread at one end, an internal 70 thread at the upper end, a burner tip threadably connected to said tubular member at its upper end, said burner tip having a convex lower side, and having a conical shaped orifice through its center, an atomizing screen 75 located within the said burner, means of holding said screen in position and means of removing the same, substantially as set forth.

In testimony whereof I affix my signature. 80
FRANK BINSFELD.
